AUGUST SUNDH, OF YONKERS, NEW YORK, ASSIGNOR TO OTIS ELEVATOR COMPANY, OF EAST ORANGE, NEW JERSEY, A CORPORATION OF NEW JERSEY.

SYSTEM OF ALTERNATING-CURRENT-MOTOR CONTROL.

No. 824,756.

Specification of Letters Patent.

Patented July 3, 1906.

Application filed March 10, 1905. Serial No. 249,430.

To all whom it may concern:

Be it known that I, AUGUST SUNDH, a citizen of the United States, residing at Yonkers, in the county of Westchester and State of New York, have invented certain new and useful Improvements in Systems of Alternating-Current-Motor Control, of which the following is a specification.

My invention relates to a system of alternating-current-motor control, and more particularly to an automatic push-button-controlling system as applied to the operation of electric elevators.

The object of the present invention is to provide a simple and positive controlling device which will overcome the many difficulties met with in alternating-current systems in use at the present time.

The accompanying drawing shows the application of my invention to an elevator system for three floors operated by push-buttons and is more or less diagrammatic in character and illustrates a three-phase power-circuit and single-phase operating-circuits.

25 The characters *a*, *b*, and *c* designate a three-wire two-phase-current supply.

10 is a main-line switch, and 15 is a three-pole switch.

20 and 30 designate motor starting and reversing switches.

40 represents an alternating-current hoisting-motor, and 45 slip-rings on the rotor-shaft.

50 designates the releasing-magnet, which 35 operates a friction-brake.

60 is a resistance connected through brushes to the rotor-winding.

70 and 75 are the accelerating-switches which operate this short circuit or cut out 40 more or less of the three-phase star-connected resistance 60.

85 is a self-holding safety-magnet, and 90 a non-interfering magnet.

11, 22, and 33 are floor magnets or relays, 45 directly under which are five rings comprising the floor-controller. These five rings are rigidly mounted on the same shaft 16, which is positively driven by some moving part of the hoisting-machine.

50 1, 2, and 3 designate push-buttons located at or near the various floor-landings, and 1', 2', and 3' are the landing-door contacts.

4 represents a small slack-cable switch.

7 designates a junction-box, preferably placed in the center of the shaft

5 is the elevator-car, which has its side cut away in order to show the push-buttons 12, 13, and 14, the gate-contact 8, and safety-button 9.

6 6 are hoisting-cables carrying the car 5.

The light black lines represent the operating-circuits, while the heavy black lines represent the main-line and motor circuits.

In alternating-current-controlling systems in use at the present time there is uncertainty and unreliability of proper operation, coupled with a complicated electrical circuit including a multitude of wires. It is therefore extremely difficult to keep the system in proper working order. My invention does away with the complicated system of wiring to a great extent and at the same time can be adapted to an alternating current of single or multi phase without any radical change in the controlling apparatus.

Generally speaking, the operation of my invention may be pointed out as follows: On pushing one of the operating-buttons a circuit is completed through a corresponding floor-relay, which operates to close a circuit through one of the motor-starting switches.

At the same time switches are electrically operated to prevent any interference from other possible circuits and to insure a correct operation of the system. The motor is set in motion when a circuit is established by one of the two reversing-switches 20 and 30, a friction-brake being released as soon as the motor receives current.

Directly the motor has started or very shortly thereafter switches, 90 influenced by the drop of potential in the rotor-windings as the same accelerates, cut out or short-circuit in consecutive steps portions of a star-connected resistance in the rotor-circuit, thereby producing a smooth and 95 gradual acceleration from a state of rest to normal full speed. The circuit through the floor-relay being broken by the operation of the floor-controller when the elevator-car has reached the desired landing, the brake

100 will be applied and the hoisting-machine brought to rest ready for the next operation.

In order to more fully describe the operation of my system and at the same time to

show clearly the function of each of the several parts, it will be supposed that there is power on the two-phase or three-phase supply-mains *a*, *b*, and *c*, and the manually-operable switches 10 and 15 are closed, as shown in the drawing. This will connect the wires 17, 18, and 19 to the supply-mains *a*, *b*, and *c* and cause them to become charged. The wire 17 is connected directly to the two middle terminals of the stator-winding of the motor 40 at the terminal block 29. The wire 18 is connected to two contacts 34 and 23 on the reversing-switches 30 and 20, respectively. The wire 19 is connected to the contacts 33 and 24 on these same switches. The switches 20 and 30 are of similar construction, so a description of one will apply equally as well to the other. The switch 20, for example, comprises a framework carried on a magnet-plunger 28. At the upper ends of this framework, but insulated from it, are mounted the contacts 23 and 24, adapted to engage the fixed contacts 21 and 22, respectively, said fixed contacts being directly above and in the path of travel of the movable contacts. The contact 25 is in like manner attached to the framework of the switch 20 and when the switch is in its downward position rests upon and makes contact with the fixed contact 26. Whenever the core 28 is sufficiently energized by the magnet-coil 27 to raise the framework and the contacts mounted thereon, the contacts 23 and 24 will engage the fixed contacts 21 and 22, respectively, while the contact 25 will be raised out of engagement with the fixed contact 26.

In order to trace the circuit to the motor, it will be necessary to operate either the switch 20 or 30. Let it be assumed that the switch 20 has been operated so as to be in its upward or closed position. The contact 23 will now engage contact 21 and the contact 24 will engage 22. This will establish a connection between the wires 18 and 39 and also between 19 and 41. The motor will now be connected to the supply-mains *a*, *b*, and *c*. At the same time the brake-magnet 50 will receive current, since it is connected to the same wires which supply the motor with current and will be energized to release the brake. The brake being of any preferred construction employing a spring or its equivalent to apply the brake and having magnetic means to release the same, the motor will now be free to start and will operate to raise or lower the elevator-car, as the case may be. The rotor-winding has three taps or connections leading to the slip-rings on the rotor-shaft. Connection is made with these rings by the brushes 42, 43, and 44 in a well-known way. A wire connects brush 42 to the resistance 60 at the point *d*, also to the contact 48. Brush 43 is connected to *e* and 47, while brush 44 is connected to *f* and 46. Intermediate points of the resistance 60—

such as *g*, *h*, and *k*—are connected, respectively, to the contacts 57, 58, and 56 of the switch 70.

The switches 70 and 75 are similar in construction and each comprises three fixed contacts—such as 58, 56, and 57—directly under which are three movable contacts 59, which are connected together and are mounted upon, but insulated from, the plunger 52. The plunger 52 is rigidly connected to the plunger 53. 51 represents a magnet-coil so placed with regard to the plunger 52 that when fully energized it tends to raise the plungers 52 and 53, together with the contacts 59, which latter will engage the fixed contacts 58, 56, 80 and 57, placed directly above them. The magnet-coil 54 is so placed with respect to the plunger 53 that when energized it tends to draw the plunger in a downward direction. The same description will apply to the switch 75, the magnet-coil 63 acting in opposition to the magnet-coil 62, which latter tends to raise the three contacts 49 into engagement with the three fixed contacts 48, 46, and 47. 55 and 61 are resistances of different values 90 which check the current to their respective magnet-coils 54 and 63, the resistance 55 being greater than the resistance 61.

The operation of the accelerating-switches 70 and 75 is as follows: As soon as the stator or primary is connected to the two-phase or three-phase source of supply by means of the reversing-switch 20 or 30 the two magnet-coils 51 and 62, being connected in parallel to each other, will be at once energized, since 100 their source of current-supply is identical with that of the stator-winding. The magnet-coil 54, having the resistance 55 in series with it, and the magnet-coil 63, having the resistance 61 in series with it, are in parallel to 105 each other and are connected to the motor-brushes 42 and 44. The motor armature or rotor being at rest, the voltage induced therein is at a maximum until the rotor begins to revolve, and since the magnet-coils 54 and 63 110 are connected to the rotor-windings the potential across these coils will be proportional to the induced voltage existing in the secondary of the motor. For this reason the magnet-coils 54 and 63 will exert their maximum 115 power at the moment of starting, overcoming the tendency of the magnet-coils 51 and 62 to raise their respective plungers. Thus upon starting the motor the resistance 60 remains in series with the secondary or rotor 120 winding in order to keep down the starting-current and give the motor the necessary starting torque. As soon as the rotor begins to revolve the induced voltage therein will, drop proportionately to the speed, producing 125 a proportional drop of potential across the magnet-coils 54 and 63, and consequently a less powerful downward pull will be exerted upon their respective plungers. As long as the primary of the motor is connected to the 130

source of current-supply and the voltage of the supply remains constant the upward pull of the magnet-coils 51 and 62 will remain constant. The voltage, and consequently the magnetizing power of the magnet-coils 54 and 63, which oppose the action of the coils 51 and 62, respectively, will grow less and less as the motor speeds up until finally the pull of the magnet-coil 51 will overcome that of the magnet-coil 54 and the contacts 59 will be raised until they engage the three contacts fixed directly above. This is due to the fact that the resistance 55 is greater than the resistance 61, and consequently less current flows in the coil 54 than in the coil 63. This operation will short-circuit a portion of the resistance in series with the secondary winding, allowing the motor to assume a higher speed. The induced voltage in the secondary, owing to this increase of speed, will drop still lower until finally the magnet-coil 62 overpowers the coil 63 and raises the three contacts 49 into engagement with the contacts 48, 46, and 47. This last operation short-circuits the secondary or rotor winding and the motor attains full speed. If the reversing-switch 30 had been operated instead of the switch 20, the only difference would have been to inter-change the connections leading to the outside terminals of the primary winding of the motor. The wire 17 remaining connected to the two inside terminals, this would cause the motor to revolve in an opposite direction.

The operation of the push-buttons 1, 2, 3 and 12, 13, and 14 will now be explained. Starting at the point 64 where the feed-wire of the operating-circuit connects onto the main line *a* and passing through the limit-switches 65 and 66, which are normally closed, a circuit leads by wire 67 to one terminal of each of the magnets of the floor-relays 11, 22, and 33. The wire 67 also leads to the contact 68, where the circuit is normally open. The other terminals of the floor-magnets 11, 22, and 33 are connected, respectively, to the wires 72, 71, and 69. The wire 72 is normally open-circuited at the push-buttons 1 and 12 and at the brush 73. The wire 71 is open-circuited at brush 74 and push-buttons 2 and 13, and the wire 69 is open-circuited at brush 76 and push-buttons 3 and 14. Therefore in order to complete a circuit through any one of the floor-relays it will be necessary to operate one of the push-buttons. Assuming that the landing-button 3 has been pushed, a circuit will be closed from wire 67 by way of magnet-coil 33, wire 69, through the button 3, and by wire 77 to one terminal of the inductive resistance or impedance coil 80. The other terminal of the resistance 80 is connected to a fixed contact 78 of the non-interference switch 90. The inductive-resistance coil 80, with its core 80', constitutes a compensating resistance for the hall-button circuit. This compensating resistance is so constructed as to be the electrical equivalent of the non-interference relay 90, so that the current through a floor-relay will be substantially the same whether a car or hall button is operated.

The contact 78 is normally connected by the contact-plate 79 to the fixed contact 81, being connected to contacts 25, 26, 36, and 35. This last contact 35 is connected by wire 82 to one terminal of each of the reversing-switch coils 27 and 37 and by wire 83 to the coil of the safety-magnet 85 and the safety-button 9 in the elevator-car. The circuit is normally open at these latter connections except at the button 9, which is normally closed. Continuing, the circuit may be traced through the normally closed gate-contacts 3', 2', and 1', the slack-cable switch 4, line-wire 86, to the wire 17 and main-line lead *b*. On reviewing the circuit just traced it will be seen that the magnet-coil of the floor-relay 33 and the inductive resistance 80 are in series in a single-phase circuit across the mains *a* and *b*. The circuit to the reversing-switch coils 27 and 37 is normally open at the floor-controller rings mounted on the motor-shaft 16. The magnet of the relay 33 will now be energized to raise its core, to which is connected the insulated brush 76, this latter being connected to the wire 69, but insulated from the rest of the relay 33. The relays 11 and 22 are similarly constructed. At the same time that relay 33 is energized the inductive resistance 80 is energized and raises its plunger, which heretofore protruded but a short portion of its length, into the magnetic field set up by its coil. As the core or plunger of resistance 80 is raised less current flows in the circuit including said resistance 80 and the floor-relay 33, owing to the increased inductive or choking effect produced by decreasing the magnetic reluctance of said coil 80. This core is so arranged that the movements thereof, and consequently the effect on the current, shall be substantially the same as the movements of the core 93 and the effect thereof on the current flowing in the coil of the non-interference magnet. The upward movement of the core of the magnet of relay 33 will cause the brush 76 to come into contact with the contact-ring 87. The ring 87 is connected by wire to the contact-ring 88, and this is connected by wire 89 to coil 27 of reversing-switch 20. The operation of the floor-relay has caused a circuit to be completed through the reversing-switch coil 27 from wire 69 in parallel to the inductive-resistance coil 80, and this parallel circuit is in series with the magnet of floor-relay 33. As soon as the magnet 27 receives current it will be energized to raise its plunger 28 to start the

motor in such a direction as to raise the elevator-car, as before pointed out; but when the switch 20 is operated the contacts 25 and 26 are separated, and by so doing the circuit 5 through the inductive resistance 80 is interrupted, causing the latter to be cut out of circuit.

A circuit comprising the limit-switches, the floor-relay 33, the reversing-switch magnet 10 27, the safety-button 9, the gate-contact 8, door-contacts 3' 2' 1', and slack-cable switch 4, all in series across the supply-mains *a* and *b*, has been established. The elevator is now 15 ascending at full speed and the five contact-strips on the floor-controller will all be revolving in a left-hand or counter-clockwise direction, as indicated by the arrow marked "up" on the drawing. As the elevator-car arrives at the desired landing, in this case 20 the third floor since button 3 was operated, the contact-strip 87 of the floor-controller will run off the brush 76 of the floor-relay 33, causing the circuit through the magnet of reversing-switch 20 to be broken, allowing 25 the latter to drop its plunger. The motor will then be stopped by the application of the brake. From the above it will be seen that as soon as the reversing-switch was operated it caused the circuit feeding the landing-buttons 1, 2, and 3 to be broken, thus 30 rendering any operation from these buttons to be of no effect so long as the reversing-switch 20 is in a position to start the motor. The position of the floor-controller, as shown 35 on the drawing, indicates that the elevator is at the first or lowermost landing, making it impossible to operate the switch 30 at this time. If after the floor-controller has been revolved, as first described in connection 40 with the car going to the third floor, and the contact-strip 87 has been carried out of engagement with the brush 76 and the car has been brought to rest, the landing-button 1 were pressed, the floor-relay 11 would operate 45 to cause the brush 73 to engage the contact-strip 91. This would cause a circuit to be established as before, only in this case the circuit would be completed through the wire 92 and magnet 37 of the reversing-switch 30 and the motor would be started to lower the 50 elevator-car, the car being brought to rest at the first floor when the contact-strip 91 runs off the brush 73, the reversing-switch 30 dropping to normal position. The contacts 55 35 and 36 are separated by the upward movement of the switch 30, which produces a result similar to that produced when the switch 20 was operated—viz., breaking the circuit through the inductive resistance 80 and the landing-button feed-wire 77. Since 60 the operating-circuit includes the safety-button 9, gate-contact 8, door-contacts 1', 2', and 3', the slack-cable and limit switches 4, 66, and 65, respectively, and a fuse 98 in 65 each side of the circuit, the operation of any

one of these while the motor is running will break the circuit to the reversing-switches, causing the motor to come to rest.

The non-interference switch 90 and the self-holding locking-switch 85 will now be described. These magnet-switches comprise plungers surrounded by magnet-coils, and the upper end of each plunger is connected to a rocker-arm pivoted at 91. Therefore as one plunger rises the other will descend, and vice versa. The plunger 93 on account of the weight 92 will always assume its lower position when the magnet-coils of 85 and 90 are not energized. At the lower end of each of the plungers 94 and 93 are contact-disks having a small vertical movement against the tension of the small springs shown directly above them. In the path of travel of these contact-disks are fixed contacts 68, 96, 78, and 81—two for each switch. When the switches are in their normal position, the contact-plate 79 of switch 90 connects the contacts 78 and 81 together. When the contact-disk 95 of switch 85 is in its lower position, it connects the contacts 68 and 96 together. 90

The operation of the car-buttons is as follows: As before, the circuit may be traced from wire 64, leading by way of the limit-switches 65 and 66 and wire 67 to the terminals of the magnets of the floor-relays 11, 22, 95 and 33. Circuits 72, 71, and 69 lead from the relays 11, 22, and 33 to the car-buttons. On pressing the button 14 a circuit is closed to wire 97 and magnet of switch 90 and by wire 83 through the contacts of 9 8 3' 2' 1', slack-cable switch 4, to the main line *b*, through wire 17. The magnet of the floor-relay 33 will be energized and will cause the brush 76 to engage the floor-controller strip 87, which will complete a circuit through the reversing-switch 20 to start the motor in the same manner as was done in the case described before when the landing-button was operated. The magnet of switch 90 when energized will operate to raise the plunger 93 to disconnect the contacts 78 and 81, open-circuit the feed-wire to the landing-buttons, and thus prevent any interference should these buttons be manipulated. When the magnet 90 raises its plunger, the plunger 94 of the magnet-switch 85 will be forced downwardly until the contact-disk 95 will engage the contacts 68 and 96. This will at once cause the magnet of switch 85 to be energized to hold down its core. The magnet-switch 85 receives current at nearly the full-line potential across the mains *a* and *b*, the circuit starting from main *a* being through 67 68 95 96, magnet of switch 85, lead 83, button 9, gate-contacts 8, 3', 2', and 1', and through lead 86 to 17 and main *b*. It 115 will therefore be seen that the switch 85 is a self-holding safety-switch. As soon as the car reaches the third-floor landing, the floor-controller will, as before, break the circuit 120 supplying the reversing-switch 20. The 130

floor-relay 33 will also be deenergized, as the button 14 was closed from 69 to 97 only at the beginning of the operation. The motor will therefore come to rest. The circuit to the safety-magnet 85 will remain unbroken. Consequently its own circuit will be maintained through the contacts 68 and 96. So long as this circuit is unbroken operation of the landing-buttons 1, 2, and 3 will have no effect. As the car-gate is opened, however, to allow the operator to get out from the car the circuit through the magnet 85 will be broken at the gate-contact 8, allowing the plunger 94 to rise, due to the weight 92. Then the contacts 78 and 81 will once more be connected by the disk 79, making it again possible to operate the car from the landing-buttons after the doors are all closed. Should the car for some reason overrun its travel, the limit-switches will operate to open the circuit leading to the reversing-switches, which would cause the motor to come to rest. As an extra preventive for the car overrunning arms might be mounted upon the floor-controller shaft 16, which would open the switch 15 or a manually-closed switch in the circuit 67 if the floor-controller should revolve past its normal travel. One arm would be operative at the extreme upper limit and another arm at the extreme lower limit.

It has been shown how the various push-buttons by their operation cause the energization of corresponding floor-relays and how the floor-controller, which acts in conjunction with the floor-relays and the hoisting machinery, makes an automatic operation possible. The car always goes to the desired floor and stops there automatically whether operated from the landing or from the car buttons. The car can be stopped at any point in its travel by merely pressing the button 9, which normally closes the circuit in which it is placed, the operating-circuit in every case being completed through said button 9.

The system described is well adapted to an alternating-current circuit of any phase. The operating-magnets may be placed across a suitable pair of leads of the multiphase circuit, the only requisite being that the current passing through the magnets shall be single phase to simplify the wiring. In the three-wire two-phase motor-circuit, as shown in the drawing, or in a three-phase motor-circuit the operating-magnets of the push-button system may be placed across any two leads. The operating-magnets are shown placed across the mains *a* and *b*; but it is obvious that they could be placed across mains *a* and *c* or across mains *b* and *c*.

I do not herein claim the specific means for accelerating the motor, as this specifically is the invention of David L. Lindquist and is described and claimed in an application copending herewith. The brake-magnet

shown connected to my electric elevator-controlling system may be such as disclosed in the patent to Lindquist, No. 744,773, granted November 24, 1903, in which particular attention is directed to Fig. 6.

Without limiting myself to the precise construction of details herein disclosed, but reserving the right to make such changes as fall within the spirit and scope of my invention, what I claim as new, and desire to secure by Letters Patent, is—

1. The combination with an alternating-current motor, of controlling means therefor, and an electroresponsive device arranged to control a single-phase circuit to said motor-controlling means.

2. The combination with an alternating-current motor, of controlling means therefor, and an electroresponsive device connected in a single-phase circuit to mains of said motor, said electroresponsive device being so constructed and arranged as to control a circuit to said motor-controlling means.

3. The combination with an alternating-current motor, of motor-controlling means, circuits and connections of an automatic push-button-controlled elevator system comprising a single-phase magnet and a floor-controller, said circuits and connections being so constructed and arranged that when said magnet is energized a circuit shall be closed to said motor-controlling means through said floor-controller.

4. The combination with a multiphase motor, of motor-controlling means; circuits and connections of an automatic push-button-controlled elevator system comprising single-phase magnets corresponding to the various floors, and a floor-controller; said circuits and connections being so constructed and arranged that when one of said magnets is energized a single-phase circuit shall be closed to said motor-controlling means.

5. The combination with a multiphase motor, of motor-controlling means, and circuits and connections of an automatic push-button-controlled elevator system comprising a single-phase magnet arranged to be operated from the car to prevent interference from the landing push-buttons.

6. The combination with a multiphase motor, of motor-controlling means, and circuits and connections of an automatic push-button-controlled elevator system arranged to be energized by single-phase current, said circuits and connections comprising a non-interference magnet controlled from the car and a holding-magnet controlled by said non-interference magnet.

7. The combination with an alternating-current motor, of motor-controlling means, circuits and connections of an automatic push-button-controlled elevator system comprising a single-phase non-interference magnet controlled from the car, a compensating

- inductive resistance controlled from a landing, and floor-relays controlled from either, said parts being so constructed and arranged that whether a car or hall button is operated 5 the current through a floor-relay shall be substantially the same.
8. The combination with alternating-current-motor controlling means, a relay for automatically controlling a circuit to said 10 motor-controlling means, an inductive resistance in a normally open circuit with said relay, means for manually closing the circuit between said relay and inductive resistance, and means for breaking the circuit to 15 said inductive resistance upon the operation of said motor-controlling means.
9. The combination with alternating-current-motor controlling means, of an electro-responsive device for controlling a circuit to 20 said motor-controlling means, an impedance-coil in circuit with said electroresponsive device, a movable core for said impedance-coil, and means for interrupting a circuit to said 25 impedance-coil as soon as the normal relation of parts of said motor-controlling means is changed.
10. The combination with an alternating-current motor, of motor-controlling means therefor, an electroresponsive device arranged to control a circuit to said controlling 30 means, a choke-coil in circuit with said electroresponsive device, and electric circuits and connections so arranged that upon the 35 operation of the motor-controlling means the circuit to said choke-coil is broken.
11. The combination with an alternating-current motor, of motor-controlling means therefor, a relay arranged to control a circuit to said motor-controlling means, a choke-coil 40 in a circuit in parallel with said relay, a movable core for said choke-coil, and means for interrupting a circuit to said choke-coil after the circuit to said floor-controlling means has 45 been established.
12. The combination of a multiphase motor, with a source of alternating-current supply comprising main lines, motor-controlling means, an electroresponsive device for controlling a circuit to said controlling means, 50 an inductive resistance in circuit with said electroresponsive device, a circuit including said electroresponsive device and said inductive resistance and placed across two of the mains of the source of supply.
13. The combination of a multiphase motor, with a source of alternating-current supply of three or more phases, said source comprising main lines; motor-controlling means, circuit-controlling means for controlling a 55 circuit to said motor-controlling means, an inductive resistance in circuit with said circuit-closing means, and a circuit, including said inductive resistance, connected across a pair of said mains.
14. The combination with a three-phase 60 motor, of a source of alternating-current supply comprising main lines; means comprising a single-phase magnet for controlling said motor; a single-phase relay-magnet, means operated thereby for controlling a circuit to 65 said motor-controlling magnet, an impedance-coil in circuit with said relay-magnet, a movable core for said impedance-coil, and a circuit including the said magnets and impedance-coil and arranged to be connected 70 across any two of said main lines.
15. The combination with a two-phase motor, of a source of alternating-current supply comprising three main lines; means comprising a single-phase magnet for controlling 75 said motor; a single-phase relay-magnet, means operated thereby for controlling a circuit to said motor-controlling magnet, an impedance-coil in circuit with said relay-magnet, a movable core for said impedance-coil, and a circuit including the said magnets and impedance-coil and arranged to be connected 80 across any two of said main lines.
16. The combination with a multiphase motor, of a source of alternating-current supply 85 comprising main lines; an electromagnetic motor-controlling means, a relay, a variable inductive resistance in circuit with said relay, and circuits and connections connected across two of said main lines and so arranged that when the circuit to said relay and inductive resistance is closed a circuit is automatically closed to said electromagnetic motor-controlling means after which the circuit to said inductive resistance is automatically interrupted.
17. The combination with a car and its motor, of stations, motor-controlling means, an electroresponsive device for controlling a circuit to said motor-controlling means, an inductive resistance in a normally open circuit, and means at said stations for closing a circuit between said electroresponsive device and said inductive resistance.
18. The combination with an elevator-car 90 and its motor, of motor-controlling means, a relay, a variable inductive resistance, means at the landings to close a circuit between said relay and inductive resistance whereby a circuit is closed to the motor-controlling means, and means operating in conjunction with said motor-controlling means to then break the circuit through said inductive resistance and circuit-closing means at the landing.
19. The combination with an elevator-car 95 and its motor, of motor-controlling means, a relay, electric circuits and connections and push-buttons to automatically control the travel of said car, an inductive resistance in a normally open circuit with the push-buttons at the various landings, whereby when a circuit is closed between said inductive resistance and said relay by the operation of a landing push-button said relay controls a circuit to said motor-controlling means after 100

- which the circuit to said inductive resistance and landing push-buttons is automatically interrupted at said motor-controlling means.
20. The combination with an elevator-car and its motor, of motor-controlling means, a push-button at each landing, push-buttons in the car corresponding to the landing push-buttons, an inductive resistance connected to the landing push-buttons, relays connected to the landing push-buttons and car push-buttons, and electric circuits and connections so arranged that when a landing push-button is operated a circuit is closed between said inductive resistance and one of said relays whereas if a car push-button is operated a circuit is closed to only one of said relays, said relay closing a circuit to said motor-controlling means after which the circuit to said landing push-button and inductive resistance is interrupted.
21. The combination with an alternating-current motor, of an elevator-car, electric circuits and connections of an automatic push-button-controlled elevator system comprising a motor-controlling means, a relay for controlling a circuit to said motor-controlling means, an impedance-coil, a movable core for said coil, a landing push-button arranged when operated to close a circuit between said relay and impedance-coil and means mounted on said motor-controlling means for interrupting the circuit through said impedance-coil established by the operation of said landing push-button.
22. The combination with an alternating-current motor of the multiphase type, a source of current-supply therefor comprising main lines; an elevator-car, electric circuits and connections of an automatic push-button-controlled elevator system connected across two of said main lines and comprising motor-controlling means, a floor-controller, a relay for closing a circuit through said floor-controller to said motor-controlling means, means for controlling said relay from the car or from a landing, a variable inductive resistance connected in circuit with said relay when said landing-controlling means is operated, and means for interrupting the circuit to said inductive resistance after said relay has operated.
23. The combination with a two-phase motor and three supply-mains therefor, of an electric car arranged to be operated thereby, electric circuits and connections of an automatic push-button-controlled elevator system connected across any two of said main lines and comprising motor-controlling means, relays for closing circuits to said motor-controlling means, a variable inductive resistance, push-buttons one at each landing for closing circuits between said relays and inductive resistance, and means for rendering said landing push-buttons inoperative prior to the starting of the said motor.
24. The combination with a motor and motor-controlling means, of an electroresponsive device for closing a circuit to said motor-controlling means, a variable inductive resistance, a switch for closing a circuit between said variable resistance and said electroresponsive device, means connected with said motor-controlling means for interrupting the circuit to said inductive resistance and additional means for interrupting said last-mentioned circuit and maintaining the same interrupted until after the motor has stopped.
25. The combination with a motor and motor-controlling means, means for controlling a circuit to said motor-controlling means, an inductive resistance, a switch for closing a circuit between said circuit-closing means and said inductive resistance, means for interrupting the circuit to said switch and closing a circuit to render said switch inoperative until said last-mentioned circuit is interrupted.
26. The combination with an elevator-car and its motor, of electric circuits and connections of an automatic push-button-controlled elevator system comprising motor-controlling means, means controlled from the landings or from the car to close circuits to said motor-controlling means, means operated from the car for rendering the landing-buttons inoperative, a locking-circuit closed by said last-mentioned means so arranged that said landing-buttons remain inoperative until said locking-circuit is interrupted.
27. An automatic push-button-controlled elevator system, comprising a car and its motor, means for controlling said motor, means controlled from any landing or from said car for closing a circuit to said motor-controlling means, an electromagnetic switch for interrupting the circuit to the landing-buttons to render them inoperative, a second electromagnetic switch arranged to close a locking-circuit, means connecting the two switches for maintaining said landing-buttons inoperative until the locking-circuit is interrupted.
28. An automatic push-button-controlled elevator system comprising a car and its motor, motor-controlling means, means controlled from said car or any landing for operating said motor-controlling means, a switch for interrupting the circuit to the landing-buttons, a solenoid connected to the buttons in the car, a core for said solenoid said core being connected to said switch, a locking-circuit, a second switch and a second solenoid both in said locking-circuit, a second core connected to said second switch and mechanically connected to the first core, whereby when the car push-button is operated the landing push-buttons are rendered inoperative and maintained thus by the closing of the locking-circuit until said locking-circuit is interrupted.
29. In an automatic push-button-con-

- trolled elevator system, a car and its motor, motor-controlling means; means controlled from said car or from a landing for operating said motor-controlling means; a non-interference device controlled by the buttons in the car, comprising two solenoids, cores for said solenoids, circuit-closing means at one end of said cores, a pivoted lever pivotally connected to the other end of said cores, a locking-circuit, and electric circuits and connections so arranged that when one core is in its lower position the other is in its upper position thus opening the circuit to the landing-buttons and closing the locking-circuit when a car-button is operated, and means for returning said switches to normal when the locking-circuit is interrupted.
30. An automatic push-button-controlled elevator system comprising a push-button for each floor or station, push-buttons for the car, motor-controlling means and electric circuits and connections therefor, a switch arranged to be operated as the motor is started to render the floor push-buttons inoperative during the operation of the motor, a second switch in the circuit to the floor push-buttons, electromagnetic means controlled by a car push-button for opening said second
- switch, a locking-circuit, means controlled by said electromagnetic means for closing said locking-circuit and means for holding said last-mentioned circuit closed, so arranged as to prevent the starting of the motor after being stopped until said locking-circuit has been interrupted at a predetermined point.
35. An automatic push-button-controlled elevator system comprising an alternating-current motor, circuits and connections including single-phase magnets for controlling the operation of said motor, a variable inductive resistance, manual means for closing a circuit through said inductive resistance, automatic means controlled from the car for interrupting the circuit to said manual means and inductive resistance, and means controlled by said automatic means for holding the said circuit to the manual means interrupted until after the car has come to rest.
40. An automatic push-button-controlled elevator system comprising an alternating-current motor, circuits and connections including single-phase magnets for controlling the operation of said motor, a variable inductive resistance, manual means for closing a circuit through said inductive resistance, automatic means controlled from the car for interrupting the circuit to said manual means and inductive resistance, and means controlled by said automatic means for holding the said circuit to the manual means interrupted until after the car has come to rest.
45. An automatic push-button-controlled elevator system comprising an alternating-current motor, circuits and connections including single-phase magnets for controlling the operation of said motor, a variable inductive resistance, manual means for closing a circuit through said inductive resistance, automatic means controlled from the car for interrupting the circuit to said manual means and inductive resistance, and means controlled by said automatic means for holding the said circuit to the manual means interrupted until after the car has come to rest.

In witness whereof I have signed my name in the presence of two subscribing witnesses.

AUGUST SUNDH.
